(57) **CLAIM**

The ornamental design for an electrosurgical pencil with three button control, as shown and described.

DESCRIPTION

FIG. 1 is a perspective view of the electrosurgical pencil with three button control showing the present design;

FIG. 2 is a left, side elevational view of the electrosurgical pencil with three button control of FIG. 1, the right side view being a mirror image of the left side view;

FIG. 3 is a front elevational view of the electrosurgical pencil with three button control of FIG. 1;

FIG. 4 is a rear elevational view of the electrosurgical pencil with three button control of FIG. 1;

FIG. 5 is a top plan view of the electrosurgical pencil with three button control of FIG. 1;

FIG. 6 is a bottom plan view of the electrosurgical pencil with three button control of FIG. 1; and,

FIG. 7 is a rear perspective view of the electrosurgical pencil with three button control of FIG. 1.

The broken lines showing in FIGS. 1–7 are for illustrative purposes only and form no part of the claimed design.
